WOVEN FABRIC

Henry C. Haskell, Moosup, Conn., assignor to
 Brunswick Worsted Mills, Inc., Moosup, Conn.,
 a corporation of Rhode Island

Application March 29, 1940, Serial No. 326,695

9 Claims. (Cl. 139—383)

This invention relates to a woven fabric and more particularly to a fabric woven with woolen yarn, with worsted yarn, with yarn containing a mixture of wool with other fibres, or with a combination of such yarns, which has a predominant dark diagonal visual effect of the type distinctive to sharkskin worsted and sharkskin cheviot fabrics. The fabric of this invention has, in general, the appearance of a conventional sharkskin fabric, although the distinctive sharkskin features are not as pronounced as in ordinary sharkskin fabric. However, the sharkskin features are sufficiently apparent to permit the novel fabric of this invention to compete with, and find use as a substitute for sharkskin fabrics.

Ordinary worsted and cheviot sharkskins are used extensively in the fabrication of men's suitings, and to a lesser extent for other apparel, both men's and women's, and are generally desirable because of the unique appearance of the fabric. The individuality of sharkskin is inherent in the fabric and is dependent upon the particular combination of a certain weave with a certain warp and weft design. The weave is a two-and-two twill and the warp and weft design results from interweaving alternate dark and light weft threads with alternate dark and light warp threads. Obviously, such fabrics cannot be produced on a plain single shuttle loom or on an automatic box loom, and conventional sharkskin is commonly woven on a pick-and-pick loom, one shuttle feeding the dark and the other shuttle feeding the light weft thread in alternation.

I have discovered that it is possible to weave on automatic looms a fabric, which, for the purposes of the trade, simulates the distinctive sharkskin features sufficiently to permit the use of the fabric as a sharkskin substitute but which, in fact, has an individual pleasing and unique appearance due to the presence of weft threads, not of two different shades in alternation as in conventional sharkskin, but of a single same shade.

One highly important feature of the fabric of this invention, then, is that it may be woven on an automatic plain or box loom, thereby not only increasing the speed of production but lessening labor costs to such an extent as to permit a substantial price reduction and proportionate saving to the consumer, who can accept it as a completely satisfactory substitute for the more expensive conventional sharkskin.

Of almost equal importance in evaluating the advantages of the fabric of this invention over conventional sharkskin is its superior uniformity of

appearance. In conventional sharkskin, having alternate dark and light shade worsted yarns in both the warp and the weft, the manufacturer meets a serious problem in the matter of rejects. All worsted or woolen yarns vary so in size due to spinning or other variations inherent in the yarn manufacture, that, when woven into a fabric, a light or dark colored yarn in a portion of a pick or in a portion of a warp will stand out, and so catch the eye in contrast to a dark or light colored adjacent yarn that the even appearance of the design is marred. Conventional sharkskin fabrics must always be examined for these imperfections. Since, however, their occurrence is almost completely unavoidable, conventional sharkskin rejects may run high and usually exceed 5% of a total production. Even so-called regular goods, which are acceptable, are characteristically and undesirably uneven in appearance. As will be seen, where a weft yarn of a single shade is utilized, as in the fabric of this invention, imperforations of the type just enumerated will be entirely obviated so far as the weft is concerned, thus reducing by half the possibility of unevenness in appearance. As a matter of fact, it has been found that the uniformity of appearance of the fabric of this invention is such that there are only isolated instances of rejects due to the type of imperfection under discussion.

It has been found that if the color and shade of the single weft yarn used in the manufacture of the fabric of this invention is chosen with due regard to the colors and shades of alternating dark and light warp yarns so that the ultimate fabric comprises an interweaving of yarns of three shades, of the same color, the three-shade fabric, when woven in two-and-two twill, will present a design and appearance not only highly pleasing and individual but such as to convey to the eye an impression sufficiently similar to that imparted by a conventional sharkskin fabric as to permit the sale and use of the fabric of this invention as a substitute—but by no means an inferior substitute—for conventional sharkskin, and at a substantial saving in manufacture cost. The preferred fabric herein described is thus produced by utilizing a two-and-two twill weave with dark and light warp yarns alternating in the warp and with a single same weft yarn interwoven with the warps and having a color and shade so chosen with regard to the colors and shades of the warp yarns that the resulting fabric will have the desired appearance. The fabric, then, in its simplest form, is a three-shade

fabric as distinguished from a conventional two-shade or four-shade sharkskin and has therefore in certain of its aspects a different appearance from conventional sharkskin fabric, though the difference in appearance is not as pronounced as the similarity.

Preferably, as in conventional sharkskin, the warp yarns are of two different shades. Under such circumstances, the single shade weft yarn may be of the same general color as both the warp yarns, but, in any case, the shade of the single weft yarn should be intermediate, and desirably approximately half-way between, the two shades of the warp yarns.

For example, in the drawing there is shown an enlarged fragment of a fabric manufactured in accordance with this invention. In this drawing, the vertical yarns represent warp yarns and the horizontal yarns represent weft yarns. Thus, the warp yarns include a set of light warp yarns 10 interspersed alternately with dark warp yarns 20 and the weft yarns 30 are of a third shade and substantially all identical in shade, these weft yarns being interwoven with the warp yarns in a two-and-two twill as shown.

The invention may be applied in the production of fabrics of a multitude of colors. For instance, if the warp yarn includes white and black alternate yarns, a gray weft yarn may be used. Likewise, three shades of blue, three shades of brown, three shades of green, or three shades of other colors may be incorporated in the production of fabrics of this invention. In addition, white plus two shades of blue, brown, green, respectively, etc., may be employed. Thus, in each case, the 35 lightest shade found in one set of warp yarns, 10 in the drawing, may approach or even be white, and the darkest shade found in the other set of warp yarns, 20 in the drawing, may approach or even be black. The three shades do not have to be all of the same color, but are preferably so. With some colors, such as green and blue, a judicious intermixture is possible without departing from the invention. For instance, a blue shade in a weft may be incorporated with two 40 shades of green warp yarn.

Such fabrics, woven with a two-and-two twill weave of the type shown in the drawing, will present what can be called a left-handed "staircase" effect, due, as the drawing reveals, to the presence of predominant dark diagonal staircase-like broken lines extending from the bottom right of the fragment to the top left. One of such diagonal lines is indicated by the extension line 50 A—A. Upon close inspection, it will be revealed that the dark line effect A—A is formed by the continuous adjacency of dark and intermediate shade yarns only. Each of the dark diagonals like A—A is separated from an adjacent dark diagonal by a predominantly light diagonal such 55 as B—B, formed by the continuous diagonal adjacency of white and intermediate shade yarns only.

The diagonals extending in the opposite direction, that is, from bottom left to top right, present 60 quite a different appearance, involving either continuous alternating adjacency of dark and light shade yarns only, as in the diagonal C—C, or solid continuous adjacency of intermediate shade yarns, as in the diagonal D—D. The left to right diagonal D—D is therefore of the intermediate shade. The left to right diagonal C—C, being a composite of light and dark shade yarns only, gives a blend effect equivalent to the intermediate shade. On the other hand, the right to left 70

diagonals both give the effect of blends, one of which, A—A, being a composite of the dark and intermediate shade yarns only, gives a total effect equivalent to a shade just under dark, and the other of which, B—B, being a composite of light and intermediate shade yarns only, gives a total effect equivalent to a shade slightly darker than light. Obviously, the contrast between diagonals A—A and B—B is much greater than any contrast between diagonals C—C and D—D. Furthermore, of the four diagonals, the diagonal A—A will tend to appear the darkest, and it is this presence of a single darkest blend diagonal, contrasted with a lightest blend diagonal, which gives the predominating distinctive left-hand "staircase" effect which is common to this fabric and to conventional sharkskin.

As will be understood, a fabric could be woven which would have a right-handed "staircase" effect by making suitable variation in the type of two-and-two twill weave utilized. That is, the heddle action, instead of being 1, 2, 3, 4; 1, 2, 3, 4; etc., would be 4, 3, 2, 1; 4, 3, 2, 1; etc. And by interspersing the latter weave with the former, a herring-bone twill may be secured with the heddle action 1, 2, 3, 4; 2, 1, 4, 3; 1, 2, 3, 4; 2, 1, 4, 3; etc.

Likewise, silk design or plaid threads may be introduced at desired points, either in the warp or the filling, but the general background weave and appearance remains the same and in accordance with the invention. Of course if plaid filling is desired, an automatic box loom or similarly acting loom will be necessary.

The individual yarn of the three different shades or mixture of shades may be produced in a number of different manners. First, of course, single ply yarn may be used, individually dyed to three different shades. Multi-ply yarn dyed in the same manner may be utilized. Moreover, the use of multi-ply yarn suggests a ready method of obtaining the intermediate shade. Thus, a two-ply weft yarn may be formed from two individual plies, one of which is the shade of the dark warp yarn and the other of which is the shade of the light warp yarn. Preferably, if two-ply yarn is used in the weft, it is also used in the warp. A further method of securing the intermediate weft shade is by spinning into a single thread filaments of two different shades, one filament shade being substantially the same as that of the dark warp yarn and the other filament shade being substantially the same as that of the light warp yarn. Other methods of preparing a weft yarn of the proper shade will readily suggest themselves to those skilled in the art.

As an illustration of a suitable worsted fabric manufactured in accordance with this invention, a two-ply both ways fabric having a yarn size of $\frac{3}{2}$'s in both the warp and the weft may be woven with a 70 by 60 count. Coarser yarn numbers and coarser constructions accentuate the sharkskin effect.

Of course the fabric of this invention may be produced by utilizing a warp of a single shade, and alternating light and dark wefts. However, such fabric would have to be woven on a pick-and-pick loom and, therefore, while it would secure the advantage of greater uniformity as compared with conventional sharkskin, it would not overcome the necessity of utilizing a pick-and-pick loom, and would not have the economic advantage over conventional sharkskin fabric of the fabric woven with a single weft thread in ac-

cordance with the preferred form of this invention.

The fabric of this invention, therefore, provides a wholly satisfactory simulated sharkskin fabric, which has unusual advantages in its relatively low cost of production and in its pleasing appearance, the latter being afforded in part by its uniformity and evenness and in part by its unique three-shade background weave.

I claim:

1. A woven simulated sharkskin fabric consisting of two sets of yarn, one of said sets forming the warp and the other forming the weft, of said fabric, one of said sets consisting essentially of alternating light and dark yarns, and the other of said sets consisting essentially of adjacent strands of yarn of the same general color as the color of one of said light and dark yarns, and of a shade intermediate the shades of said light and dark yarns, said warp and said weft being interwoven in a two-and-two twill weave and the fabric being characterized by the predominant dark diagonal visual effect in one diagonal direction distinctive to a conventional sharkskin fabric.

2. A woven simulated sharkskin fabric consisting of two sets of yarn, one of said sets forming the warp and the other forming the weft of said fabric, one of said sets consisting essentially of black and substantially white yarns alternating consecutively, and the other of said sets consisting essentially of adjacent strands of gray yarn, said warp and weft being interwoven in a two-and-two twill weave and the fabric being characterized by the predominant dark diagonal visual effect in one diagonal direction distinctive to a conventional sharkskin fabric.

3. A woven simulated sharkskin fabric consisting essentially of light and dark yarns alternating in the warp and a weft yarn of the same general color as the color of one of said light and dark yarns and of a shade approximately half-way between the shades of said light and dark yarns, said weft yarn being interwoven with said warp in successive adjacent picks in a two-

and-two twill weave, the fabric being characterized by the predominant dark diagonal visual effect in one diagonal direction distinctive to a conventional sharkskin fabric.

5. A woven simulated sharkskin fabric consisting essentially of light and dark yarns of the same general color alternating in the warp and a weft yarn of the same general color as the color of said warp yarns and of a shade intermediate the two shades of said light and dark yarn, said weft yarn being interwoven with said warp in successive adjacent picks in a two-and-two twill weave, the fabric being characterized by the predominant dark diagonal visual effect in one diagonal direction distinctive to a conventional sharkskin fabric.

10. A woven simulated sharkskin fabric consisting essentially of black and substantially white yarns alternating in the warp and a gray weft yarn interwoven with said warp in successive adjacent picks in a two-and-two twill weave, the fabric being characterized by the predominant dark diagonal visual effect in one diagonal direction distinctive to a conventional sharkskin fabric.

15. A woven simulated sharkskin fabric in accordance with the fabric claimed in claim 1, in which the weave is a herringbone two-and-two twill weave and the diagonal visual effect is in alternate diagonal directions in adjacent warp-wise panels of said fabric.

20. A woven simulated sharkskin fabric in accordance with the fabric claimed in claim 1, in which design threads are interspersed throughout the warp of said fabric.

25. A woven simulated sharkskin fabric in accordance with the fabric claimed in claim 1, in which plaid threads are interspersed throughout the weft of said fabric.

30. A woven simulated sharkskin fabric in accordance with the fabric claimed in claim 1, in which design threads are interspersed throughout the warp and weft of said fabric.

35. A woven simulated sharkskin fabric in accordance with the fabric claimed in claim 1, in which design threads are interspersed throughout the warp and weft of said fabric.

40. A woven simulated sharkskin fabric in accordance with the fabric claimed in claim 1, in which design threads are interspersed throughout the warp and weft of said fabric.

45. A woven simulated sharkskin fabric in accordance with the fabric claimed in claim 1, in which design threads are interspersed throughout the warp and weft of said fabric.

HENRY C. HASKELL.
